UNITED STATES PATENT OFFICE.

WILLIAM WALLACE DICKINSON, JR., OF LITTLE ROCK, ARKANSAS.

APPARATUS FOR BURNING BRICKS.

1,403,300.

Specification of Letters Patent. Patented Jan. 10, 1922.

Application filed December 10, 1920. Serial No. 429,610.

To all whom it may concern:

Be it known that I, WILLIAM W. DICKINSON, Jr., a citizen of the United States, residing at Little Rock, in the county of 5 Pulaski and State of Arkansas, have invented a certain new and useful Improvement in Apparatus for Burning Bricks, of which the following is a full, clear, and exact description, reference being had to the 10 accompanying drawings.

This invention relates to the art of burning bricks and has especial reference to the construction of the kilns wherein such burning is effected. The objects of the invention 15 are the provision of a cheap, serviceable and transportable covering or housing for the bricks to be burned which shall serve to retain the heated gases in contact with the bricks during the burning process and afterwards 20 transportable bodily to a succeeding kiln, thus enabling the rapid cooling and the convenient demolition of the finished kiln; the provision of a new and improved kiln construction; while further objects and 25 advantages of the invention will become apparent as the description proceeds.

Brick kilns may be divided generally into two classes, the permanent and the temporary; the permanent kiln consists of a massive 30 external shell made of fire brick or other heat resisting material, connected with suitable stacks or other draft producing appliances and adapted to be filled with unburned bricks which are afterwards baked in the same way that bread is baked in an oven. Such a kiln is decidedly economical in the use of fuel, but is expensive to construct and maintain and also to use since the bricks generally have to be handled manually 35 owing to the necessity of introducing and removing them through very small openings or doorways; they are also very slow to use because of the great length of time required for them to cool sufficiently 40 to enable workmen to enter them, and on account of the heat the work of filling and emptying them is extremely arduous. The temporary kiln consists of a pile of bricks built in the open, and until recently has 45 been considered much inferior to the permanent kiln in respect of fuel consumption, although by means of the construction described and claimed in my former patents 50 their fuel consumption can be made to compare very favorably with that of the best

permanent kilns. Whatever be the burning method employed, it has been customary to encase or "scove" the unburned bricks with a layer of burned bricks, brickbats, or fire-bricks laid in and daubed with clay, mud, or some kind of plaster sufficient for temporary purposes and broken down after the completion of the burning so as to enable ready access to the bricks inside. According to my invention I substitute for this 60 temporary scoving a casing built up of sections of heat resisting material of a comparatively permanent construction which are moved bodily from place to place as necessary in the progress of the work. 65

In the drawings accompanying and forming a part of this application I have illustrated one embodiment of my said invention although without intent to restrict myself to the particular constructions therein 70 shown except as set forth in my claims. Fig. 1 is a perspective view of a series of kilns embodying my improvements; Fig. 2 is a perspective view of the end kiln of the series; Fig. 3 is a perspective view of a preferred form of body brick for building said sections; Fig. 4 is a similar view of a preferred form of terminal brick; Fig. 5 is a perspective view of a corner section showing the method of construction; and Fig. 6 is 80 a perspective view of a partial body section showing the method of construction. 85

So far as my invention itself is concerned it is immaterial whether each kiln is independent of all others or whether they adjoin each other in a row, although the latter is more convenient and economical; and for the most convenient performance of my invention a suitable transporting device is desirable, such as a traveling crane which 90 is best located exactly over the kiln-row. In the embodiment here shown, 1, 1 represent the rails and 2 the traveling frame of such crane, 3 being the carriage and 4 the hoisting drum from which depends the cable 5. 100 Beneath this crane is a row of kilns represented generally at A, B, C, D, E of which A is being demolished, B is cooling, C is burning, D is drying and E is being built. The interior of the kilns are laid in any suitable manner, such as that shown in my patents heretofore mentioned. Along each side of the kiln-body a row of spaced bricks 6, 6 are laid on the ground and on them are built 105 the scove panels 7, 7 of my invention. The 110

bodies of these are preferably made of oblong fire-brick 8, 8 having longitudinal ribs 9 on their upper faces and complementary grooves 10 on their lower faces. The lateral 5 margins of these panels are preferably formed of special bricks 11, similar to the bricks 8 in their possession of tongues 9 and grooves 10, but having in addition a corner removed to define a projecting tongue 12. 10 The bricks are laid in fire clay, the joints being broken in the usual manner, and the exterior is also preferably plastered with fire clay as shown at 13. The heat of the first burning sets this clay so as to make the 15 entire panel a rigid permanent structure, especially if a little salt be mixed with the fire clay. The tongues of adjacent panels overlap each other and are separated by some kind of mud which will hold air without becoming hardened with the heat. 20 When the kiln has been burned and the panel cooled sufficiently for handling, fingers or hooks 15 are inserted beneath it and connected by chains 16 with a suitable cradle 25 17 carried by the cable 5, by which it is transported to a corresponding location on a succeeding kiln, thus scoving the same much more quickly and cheaply than they can be built by hand. Each panel is formed 30 with an aperture 18 which registers with an archway in the kiln, thus providing for firing.

At the ends of the row, or at the ends of each kiln where the same are built separately, similar panels 7^a, 7^a are employed as shown in Fig. 2, the corners preferably consisting of special elements 20, 20 which are built up as shown in Fig. 5 out of the blocks 11. These blocks are bonded together by 35 overlapping, a part of the tongue being broken off as shown at 9^a to permit this. The corners are preferably applied last, their tongues overlapping those on the panels at each side. 40 The length of the tongues is such as to permit the necessary thermal expansion and contraction and also to allow for the inevitable variation in size between different kilns. While I do not restrict myself to this, I 45 recommend panels seven feet wide with tongues five inches wide. Each panel extends from its foundation to the top of the kiln. While I prefer to have this foundation a low one, I do not restrict myself thereto, especially as it may be desirable with some 50 kinds of fuel or for other reasons to build such foundation sufficiently high to accommodate the fuel apertures and employ these panels only above that point. Also I do 55 not restrict myself to a vertical setting of said panels, nor to any other details except as specified in my claims.

If by accident or use any panel becomes 60 broken or disintegrated, a new one is built 65 as at first and upon the first burning be-

comes fused into a unitary mass. The lateral joints are plastered each time with a non-ceramic mud or mortar.

Having thus described my invention what I claim is:

1. Apparatus for burning bricks comprising, in combination, a traveling crane, a row of kilns located beneath said crane, said kilns having a scoving consisting of rectangular panels of heat resistant material, and means carried by said crane whereby said panels may be transported bodily from kiln to kiln. 70

2. A scoving for brick kilns constructed of fire bricks each of which has a tongue 80 on one side and a groove at the opposite side and those among the lateral margins being rabbeted so that they are adapted to overlap similar rabbeting on adjacent panels. 75

3. A scoving for brick kilns made in 85 panels, each panel formed of a plurality of bricks having interfitting tongues and grooves laid in fire clay and burned into a rigid unitary mass.

4. A scoving for brick kilns made in 90 panels, each panel formed of a plurality of bricks having interfitting tongues and grooves laid in fire clay and burned into a rigid unitary mass the terminal bricks at 95 each side being rabbeted to overlap the adjacent scoving-member. 95

5. A scoving for brick kilns comprising rectangular panels of heat resistant brick laid in ceramic mortar and burned together, the margins of each panel being rabbeted to 100 match the adjacent scoving-members, in combination with corner pieces having rectangularly projecting portions which are rabbeted to match the adjacent panels.

6. The process of scoving brick kilns 105 which contains the steps of building a casting of heat resistant blocks arranged in panels, the margins of each panel overlapping the adjacent panels, the blocks of each panel being laid in ceramic mortar, whereby 110 the same will become rigidly fused together upon the first burning, and subsequently transporting such panels as a unit from kiln to kiln. 110

7. The process of burning bricks which 115 contains the steps of building a plurality of kilns in a row, building around the first kiln a scoving of heat resistant bricks laid in ceramic mortar and arranged in rectangular panels, burning each panel into an integral 120 unit simultaneously with burning the first kiln, and afterward transporting said panels bodily to and setting them up around a succeeding kiln. 120

8. The process of burning bricks which 125 contains the steps of building a kiln with an external scoving of heat resistant bricks laid in ceramic mortar in the form of panels, and corner pieces, adjacent scoving members being separated by non-ceramic mortar, 130

burning the scoving together, simultaneously with burning the kiln, building another kiln adjacent to the first kiln, and transporting said panels bodily to said last mentioned kiln, so as to scove the same and also enable the removal of the first kiln.

9. A portable scoving for brick kilns con-

sisting of rigid panels made of a single layer of heat resistant bricks laid in ceramic mortar in the form of rectangular overlapping panels.

In testimony whereof, I hereunto affix my signature.

WILLIAM WALLACE DICKINSON, Jr.
